W. E. WOLLHEIM

BURNER

Filed Jan. 7, 1924

INVENTOR:

Walter E. Wallheim

UNITED STATES PATENT OFFICE.

WALTER E. WOLLMHEIM, OF NEW YORK, N. Y.

BURNER.

Application filed January 7, 1924. Serial No. 684,752.

To all whom it may concern:

Be it known that I, WALTER E. WOLLMHEIM, a citizen of the United States, and a resident of New York, in the county of New York and State of New York, have invented certain new and useful Improvements in Burners, of which the following is a specification.

This invention relates to fuel oil burners, particularly the kind adapted to be used for domestic installations in which the oil is fed to the burner from a small tank by gravity, and in which air for combustion is automatically supplied by the draft in the furnace, whereby all such accessories as blowers, pumps, motors, etc., are eliminated.

It is one of the particular objects of the invention to provide a burner which will give a maximum amount of heat in proportion to the oil consumed.

Another object is to provide means which deflect the flame, if desired, partially towards the sides or the roof of the firebox of a boiler within which the burner is placed, thereby causing a quicker heating of the water or air in the boiler.

A further object is to surround the oil pipe within the burner with an air passage for cooling purposes to reduce carbonization of the oil.

A still further object is to so arrange the component parts of the burner, that the same can easily and readily be cleaned, when necessary, without breaking any joints within the burner, so that this can conveniently be done by a person relatively unskilled in the handling of mechanical devices.

Further objects are the provision of a protecting housing over the valve mechanism of the burner, a clean-out connection between its valves and the oil outlet within the burner, and the particular arrangement of piping between the burner and its valves so that erecting the same may be accomplished with the least possible expense.

Still other objects will become apparent in the following specification and the accompanying drawing which shows a preferred form of a burner embodying the aforesaid improvements, and in which

Fig. 1 is a plan view of the burner;

Fig. 2 is a vertical longitudinal cross-sectional view through the burner, taken along the plane of line 2—2, in Fig. 1;

Fig. 3 is a rear elevation of the valves of the burner and the protecting housing;

Fig. 4 is a detail fragmentary sectional view of the overflow pan, taken along the plane of line 4—4, in Fig. 2;

Fig. 5 is a fragmentary cross-sectional view along the plane of line 5—5, in Fig. 1; and

Fig. 6 is a similar view along the plane of line 6—6, in Fig. 1.

Like characters of reference denote similar parts throughout the several views and the following specifications:

10 is a grate within a furnace of which 11 is a front wall, and 12 an ash door opening.

13 is a burner base of substantially circular configuration, slightly smaller at its upper end than at its lower end which rests upon the grate 10. The top of the base is bowl shaped at 14, and has, preferably, six 75 tubular projections 15 extending therefrom to a plane in line with the top of the base, where the projections are somewhat reduced in diameter and project slightly above base 13, at 16, forming shoulders 17 in line with 80 the top of base 13.

At the lowest portion of the bowl shaped top 14 is an upwardly extending tubular projection 18 within which a tubular nipple 19 is connected integrally by means of ribs 85 20. Nipple 19 is threaded interiorly to receive at its top a vaporizer 21 consisting of an externally threaded stem 22 having a central duct 23, and an umbrella-shaped top 24. The upper surface of top 24 is provided 90 with shallow, concentrically disposed, grooves 25.

26 is an air manifold consisting of elbow like branches 27, telescoping over tubular extensions 16 and resting on shoulders 17 95 of the base 13. Branches 27 converge into a central chamber 28 which is provided with a downwardly directed outlet 29, in line with vaporizer 21 and terminating a short distance above it. At the outside of 100 the manifold 26, in its center and top, is a lug 30 having a hole 31. Near the intersections of the elbow branches 27 at the top of the manifold are sockets 32.

33 are deflector plates, placed at the top 105 of the air manifold 26, at, preferably, both sides of the burner, as shown in Fig. 1. These plates are shaped segmentally, and, in case of a six branch manifold, are each equal to one-third of the area of a circle. 110 The underside of each plate is provided with two pins 34 which fit loosely within

sockets 32 of the manifold, and with three flat lugs 35, in staggered relation to the pins 34, which rest upon the top of the three elbows 27 over which the plate is laid. 5 The diameter of these plates when measured in position and concentric with the burner is larger than that of the burner base, and therefore extends beyond the base at both sides. While the inner part of each plate 10 where it rests upon the manifold is flat at 36, its outer part is tilted at an angle at 37. 38 are lugs with holes 39, at the top of plates 33.

Screwed into nipple 19 of base 13, is a 15 pipe 40 which projects through the grate in the furnace, and terminates a little below it, where it screws into an overflow pan 41 of round cup shape. 42 is an overflow pipe screwed into bowl 14 of base 13, slightly 20 above its lowest point. This pipe is fitted or bent over at 43, within the lower part of the base and above the grate, to run closely and parallel to pipe 40 and terminates a little above, but within the outer circumference, of the overflow pan 41. The reason 25 for running the lower end of this pipe closely to pipe 40, is to facilitate the placing of the base upon the grate with both pipes 40 and 43 projecting through the grate bars. 30 At the underside of overflow pan 41 are two bosses, the one 44, being in central alignment with pipe 40, is threaded to receive an oil supply pipe 45 at right angles to pipe 40, and the other 46, being threaded to receive 35 an overflow pipe 47, substantially parallel to pipe 45, and which pipe 47 is connected to the upper cup shaped part of overflow pan 41 by means of a duct 48.

At the end of oil pipe 45, outside of the 40 furnace, is screwed a T connection 49, its outlet at right angles thereto being closed by a plug 50, its other outlet being connected to an oil regulating valve 51 of conventional needle valve design. Regulating 45 valve 51 has an elbow connection at its lower inlet which connects it with a safety trip valve 52 which is a conventional type of spring operated shut-off valve, provided with a lever 53 to the end of which is suspended a trip cup 54. The end of overflow pipe 50 47 is bent downwardly and pitched at a slight angle to terminate a little above the open top of the safety trip cup 54. 55 is an oil feed pipe which connects the safety trip valve with a feed tank.

Fitted over the rear of the safety trip valve 52 and extending frontwardly (toward the furnace), beyond its centerline, is a protecting housing 56, substantially U-shaped in cross-section. Its top 57 is closed, and its bottom 58 is flat to form a support for the housing on the floor. 59 are recesses, at both sides of the housing, to enable the same to be fitted over the pipe 60 connections to and from the safety trip 65

valve. Within the housing, at its bottom, is fitted an open pan 60, provided with a frontwardly extending lug 61, at its top.

62 is an asbestos pad placed within the bowl 14 of the burner base 13, fitting around 70 its tubular projection 18.

The grate around the burner base 13 is covered with a suitable asbestos cement 63, so as to cause all air to be drawn in through 75 the base of the burner.

The operation of the device is, as follows:

Oil is admitted by way of feed pipe 55, through the valves (the safety trip valve being wide open, the oil regulating valve 80 slightly only), pipes 45 and 40, and is allowed to dribble over the top 24 of vaporizer 21, filling its grooves 25, and accumulate at the bottom of the bowl 14 of the burner base. There the oil saturates asbestos pad 62 which is then ignited by means of a torch. 85 Within a few minutes, the vaporizer 21 is so hot, through the action of the flame from pad 62, that the oil in its grooves 25 is vaporized and is mixed with the air induced by the draft in the furnace through 90 base 13, extensions 15 and 16, and elbows 27 of manifold 26, and discharged through outlet 29. This results in combustion and causes a strong and steady flame to surround the manifold and issue from between 95 its branches into the firebox of the furnace. The intensity of the flame is regulated by means of the oil regulating valve 51. It will be noted that the flame, while passing around the manifold, automatically preheats the air supply whereby greater efficiency in combustion is achieved. The flame, after having passed through between the branches of the air manifold, is deflected at both sides of the firebox by the plates 33, while in 100 front and back the flame is projected to the roof. This results in a very even distribution of heat. By means of these plates, the burner is made adaptable to varying 105 types of furnaces, inasmuch as where a strong flame is required at the rear of the firebox, the two plates may be laid onto the manifold closely together at the front of the burner; for which reason sockets have been provided between the intersection of each 110 branch of the manifold. This, in connection with the segmental shape of the plates permits the same to be placed in any desired position on top of the manifold, and, if preferred, three plates may be used, forming 115 a closed circle at the top. In practice, the method of placing the plates at the top by means of pins and lugs, in staggered relation to each other, has been found particularly advantageous, because, in the first 120 place, they are in this manner perfectly balanced on top of the manifold, requiring no other fastening members, such as screws or hooks, etc., and can therefore with the least trouble be placed in position, and, sec-

125 130 135

ondly, the distance between the lower sides of the plates and the top of the base is so much larger than the flame outlet between the branches of the manifold, that there is no restriction to the flame, which results in a practically noiseless operation. The upwardly tilted outer ends of the plates greatly augment this feature.

In the event that there be an oversupply 10 of oil, or in other words, the burner should not vaporize all oil fed to it, or, if the flame should have been extinguished for various reasons, oil will overflow through pipe 42 into pan 41, thence into pipe 47, and gradually fill cup 54 of the safety trip valve 52. As soon as this cup is full, its weight will press lever 53 down, as shown in dotted lines in Fig. 2, and thereby release a spring 15 operated disc within the valve 52 which is thereby closed and shuts off the oil supply to the burner. Protecting housing 56 is provided to prevent injury to the safety trip valve and its cup, and to prevent spilling of oil on the floor. Drippings from the 20 trip cup 54 will accumulate in pan 60 at the bottom of the housing which pan can be emptied easily and safely.

The structural characteristics of the burner are such as to enable the same to be 25 cleaned easily and quickly by persons unskilled in the handling of mechanical appliances. A rod can easily be inserted in holes 39 of lugs 38 and the plates be lifted off. There are no catches or hooks of any kind 30 at the underside of these plates which simply rest on the top of the manifold and are guided in position and there held, in proper balance, by pins 34 and lugs 35. After having removed plates 33, in a similar manner, the manifold 26 may be lifted off by inserting 35 a rod or hook into hole 31 at its top. This exposes the vaporizer 21 which can then be scraped off or unscrewed for cleaning, if necessary. Plates and manifold may 40 easily be cleaned with a stiff brush or rag. In case of clogging of the oil supply pipe within the burner, the oil regulating valve 51 should be closed, and plug 50 removed from T 49. A flexible wire may then be 45 inserted, or, a hand air pump may be screwed in place of the plug, when a few strokes of the pump will clean out the pipe and blow out any obstructions through outlet 23 of the vaporizer.

50 It is understood that while I have shown and described above my invention, in a preferred form, as applied to one kind of burner only, its use and application may be varied and serve other kinds of burners as well.

Various changes in the form, proportion 55 and minor details of construction may be resorted to without departing from the principle or sacrificing any part of the invention as defined in the appended claims.

What I claim, as new, is:

1. In an oil burner adapted to be placed within the firebox of a boiler, plates in spaced relation with each other for the purpose of deflecting the flame from the 70 burner in any desired direction toward the sides of the firebox, and simultaneously admitting the flame, through the spaces between the plates, to the roof of the firebox.

2. In an oil burner adapted to be placed 75 within the firebox of a boiler, plates in spaced relation with each other so placed upon the burner as to deflect the flame therefrom to two sides and, through the spaces between the plates, to the front and 80 rear portion of the firebox.

3. In a burner of the character described, having a manifold for the passage of air, deflector plates on top of the manifold, and means to retain them in selected 85 positions upon the said manifold.

4. In a burner of the character described, having a manifold for the passage of air, a plurality of segmental deflector plates, on top of and projecting beyond the manifold, the outer ends of the plates which project beyond the manifold, being upwardly inclined, and means to retain them in selected 90 positions upon the said manifold.

5. In a burner of the character described, 95 a manifold for the passage of air, having a plurality of elbow shaped branches converging toward its center, sockets on top of the manifold, and deflector plates, placed on top of the said manifold, having pins en- 100 gaging the said sockets.

6. In a burner of the character described, 105 a manifold for the passage of air, having a plurality of elbow shaped branches converging toward its center, sockets on top of the manifold, and deflector plates, placed on top of the said manifold, having pins en- 110 gaging the said sockets, and lugs resting on the elbow shaped branches of the said manifold.

7. In a burner of the character described, 115 a manifold for the passage of air, having a plurality of elbow shaped branches converging toward its center, sockets at the intersections of the elbow shaped branches and on top of the manifold, and deflector plates, placed on top of the said manifold, having pins engaging the said sockets.

8. In a burner of the character described, 120 a manifold for the passage of air, having a plurality of elbow shaped branches converging toward its center, sockets at the intersections of the elbow shaped branches and on top of the manifold, and deflector plates, placed on top of the said manifold, having 125 pins engaging the said sockets, and lugs resting on the elbow shaped branches of the said manifold.

9. A deflector plate for the purpose specified, having pins near its inner underside 130

and lugs near its outer underside, in staggered relation to each other, to retain it in position upon a burner, and means at its top to conveniently remove it from such position.

10. A base of a burner of the kind described, having a bowl shaped top, a central oil supply nipple, and an overflow nipple screwed into the said bowl shaped top from the bottom at a point higher than its lowest portion, the said overflow nipple being bent over within the base to run closely and parallel to the said oil supply nipple.

11. In a burner of the kind described, a base having a bowl shaped top, a central oil supply nipple connected to the base, an overflow nipple screwed into the said bowl shaped top from the bottom of the base, at a point higher than its lowest portion, an overflow pan of open cup shape connected centrally with the said oil supply nipple, the said overflow nipple being bent over within the said base to run closely and parallel to the said oil supply nipple and to terminate slightly above, but within, the cup of the said overflow pan, and an oil

supply pipe and an overflow pipe screwed, in angular relation to the said oil supply nipple, directly into the said pan, the said pan having ducts communicating, respectively, the oil supply pipe with the said oil supply nipple, and the overflow pipe with the said open cup.

12. In a burner of the type specified, a base having a bowl shaped top and a plurality of air inlets therethrough, a central tubular projection from the said bowl shaped top, a nipple within the said projection supported in spaced relation thereto, a vaporizer screwed into the upper part, and an oil supply nipple screwed into the lower part of the said nipple, and an overflow nipple screwed into the said bowl shaped top from the bottom at a point higher than its lowest portion, the said overflow nipple being bent over within the base to run closely and parallel to the said oil supply nipple.

In testimony whereof I have hereunto set my hand and seal.

WALTER E. WOLLMHEIM. [L. s.]
